UNITED STATES PATENT OFFICE.

WILLIAM E. KEHOE, OF SAN FRANCISCO, CALIFORNIA.

DESIGN FOR A BASE FOR DISPLAY STANDS.

Application filed January 3, 1928. Serial No. 24,741. Term of patent 14 years.

To all whom it may concern:

Be it known that I, WILLIAM E. KEHOE, a citizen of the United States, residing at the city and county of San Francisco, State of California, have invented a new, original, and ornamental Design for a Base for Display Stands, of which the following is a specification, reference being had to the accompanying drawing, forming part thereof.

The figure is a perspective view of the device.

I claim:

The ornamental design for a base for display stands, as shown.

WILLIAM E. KEHOE.
